L. D. MILLER.

LEG OR SIDE FRAME FOR SEWING MACHINES.

No. 17,052.

Patented Jan. 4, 1887.

UNITED STATES PATENT OFFICE.

LEBBEUS B. MILLER, OF ELIZABETH, NEW JERSEY, ASSIGNOR TO THE SINGER MANUFACTURING COMPANY OF NEW JERSEY.

DESIGN FOR A LEG OR SIDE FRAME FOR SEWING-MACHINES.

SPECIFICATION forming part of Design No. 17,052, dated January 4, 1887.

Application filed December 7, 1886. Serial No. 220,944. Term of patent 14 years.

To all whom it may concern:

Be it known that I, LEBBEUS BALDWIN MILLER, a citizen of the United States, residing at Elizabeth, in the county of Union and State of New Jersey, have invented a new and useful Design for a Leg or Side Frame for Sewing-Machine Stands, of which the following is a specification, reference being had therein to the accompanying photographic illustration, which shows my invention in elevation.

The leading feature of my design consists in a sewing-machine leg or side frame the inner cross-bars of which are curved and recurved, so as to present a wavy appearance, the said wavy bars, as traced from the top or bottom of the leg, extending diagonally across the latter and crossing each other nearly at right angles, thus giving the effect of an open net-work. At the lower part of the leg is an oval frame, to surround any suitable ornamental figure.

A denotes the side bars of the leg or frame; B the top bar, and C the bottom bar, thereof, the said bars forming the exterior of the leg or frame. Between these exterior bars are regularly spaced wavy cross-bars D, which, as traced from the top or bottom of the leg, extend diagonally across the same, so as to cross each other nearly at right angles, thereby presenting the appearance of an open net-work; or, as traced crosswise of the leg or frame, these wavy bars present the appearance of a series of ornamental letters X joined to each other and to the side bars of the leg or frame.

Near the bottom of the leg is an oval frame, E, within which may be placed any suitable ornamental figure. In the present instance the trade-mark of the Singer Manufacturing Company is shown within the said oval frame; but the said trade-mark is not a novel feature of my design, and is not herein claimed.

The side bars, A, curve inward slightly from the top of the leg, and then recurve outward more decidedly, so that the bottom of the leg is much wider than the top. The top bar, B, is straight, or nearly so, and the bottom bar, C, is curved and recurved, in the form of a printer's brace.

I claim—

1. The design for a leg or side frame for sewing-machine stands herein shown and described, the same consisting of the top and bottom bars, the inwardly and outwardly curved side bars, and the regularly-spaced wavy diagonal cross-bars, crossing each other and joined to the bars forming the exterior of the leg or frame.

2. The design for a leg or side frame for sewing-machine stands herein shown and described, the same consisting of the inwardly and outwardly curved side bars, A, the top bar, B, the curved and recurved bottom bar, C, and the regularly-spaced wavy diagonal cross-bars D.

3. The design for a leg or side frame for sewing-machine stands herein shown and described, the same consisting of the side bars, the top and bottom bars, the regularly-spaced wavy diagonal cross-bars, and the oval frame near the bottom of the leg or side frame.

4. The design for a leg or side frame for sewing-machine stands herein shown and described, the same consisting of top, bottom, and side bars, forming an exterior frame, with which are regularly-spaced wavy diagonally-arranged bars crossing each other.

In testimony whereof I affix my signature in presence of two witnesses.

LEBBEUS B. MILLER.

Witnesses:

H. C. ELLIS,
L. L. BURRITT.
